Specification for Design.

Patented Dec. 24, 1918.

Application filed July 23, 1918. Serial No. 246,411. Term of patent 3½ years.

To all whom it may concern:

Be it known that I, JAMES F. BUNTING, a citizen of the United States of America, and a resident of the borough of Ben Avon, in the county of Allegheny and State of Pennsylvania, have invented a new, original, and ornamental Design for a Flag, of which the following is a specification, reference being had to the accompanying drawing, forming part thereof.

The figure is an elevation of a flag, showing my new design.

I claim:

The ornamental design for a flag, as shown.

JAMES F. BUNTING.
